COMPRESSIVE WAVE SENDER AND RECEIVER

Willy Kunze, Bremen, Germany, assignor to Submarine Signal Company, Boston, Mass., a corporation of Maine

Application December 5, 1933, Serial No. 701,012
In Germany January 7, 1933

7 Claims. (Cl. 177—386)

The present invention relates to apparatus for the production and reception of compressional waves, especially high-frequency waves. It has particular application to the production and reception of high-frequency compressional waves in a liquid medium such as water.

In the present invention use is made of the magnetostrictive properties of certain metals and alloys. Magnetostrictive oscillators, as devices of this type are conveniently called, have been made in the past but have not been of great value on account of their small energy output. This was in part due to the losses which occur in this type of device. It has been proposed, in order to keep the losses low, to build up the magnetostrictive vibratory body from sheet rings or laminations. A pile of such laminations is assembled with thin layers of insulating material between them and the whole pressed together so that a unitary body of definite natural frequency results.

These arrangements have the great disadvantage that at the high frequencies for which such apparatus is mostly employed large frictional losses are set up within the body of laminations. It appears that this was due to the fact that an absolutely rigid union of the individual laminae could not be assured.

An object of the present invention is to set forth a magnetostrictive vibratory body in which there is no looseness between the individual members which may give rise to undesirable frictional losses.

This is accomplished according to the present invention by employing a multiplicity of magnetostrictive members of equal length, for example, wires, thin rods, sheet strips, thin-walled tubes or the like. These may advantageously be mounted parallel to each other without metallic contact between them, their ends being rigidly joined together in some manner so that a single unitary longitudinally vibrating body results whose natural frequency can be made use of. The joining of the ends of the individual magnetostrictive members may be made either by means of insulating material or by means of one or two metallic end masses. When insulating material is used for this purpose, it may be applied in a liquid state or by means of suitable adhesive or the individual members may be pressed under pressure into the insulating material. A particularly useful construction is obtained when the ends of the individual members are rigidly joined to metallic masses as, for example, by soldering, brazing or welding.

Another feature of the invention consists in

constructing the vibratory body of the oscillator in such a manner that a different amplitude is obtained at the radiating member than the amplitude of the magnetostrictive member. This may be accomplished by employing masses of different magnitudes at the opposite ends of the magnetostrictive elements. These masses are then connected by elastic members, namely the whole or a portion of the magnetostrictive elements. In such a structure the ends of the magnetostrictive elements having the largest mass will vibrate with the smallest amplitude.

It is a known principle that a radiating surface will radiate in substantially a single direction only if its dimensions are large compared to the wave length of the energy being sent out or received. This principle may be effectively employed according to the present invention by mounting upon a radiating plate a multiplicity of magnetostrictive elements covering substantially the whole surface of the plate. Alternatively a number of magnetostrictive vibratory bodies, each composed of a plurality of magnetostrictive elements disposed parallel to but out of contact with each other and rigidly joined together at one or both ends, may be constructed. A plurality of such vibratory bodies may then be mounted upon a radiating plate of large dimensions compared to the wave length. If desired two such radiating plates may be employed, one at each end of the vibratory bodies. A directive effect may also be obtained by mounting the radiating surface or surfaces of the magnetostrictive oscillator at the focus of a parabolic reflector.

The invention may be further understood by reference to the accompanying drawing in which Fig. 1 indicates schematically the construction of a vibratory body according to the present invention; Fig. 2 is a cross section through the magnetostrictive elements along the line II—II of Fig. 1; Fig. 3 shows a cross section similar to Fig. 2 but in which the magnetostrictive elements are in the form of sheet strips rather than rods or tubes; Fig. 4 is a section through a complete high-frequency sender or receiver; and Fig. 5 shows an alternative construction of a high-frequency sender or receiver and particularly one which has two radiating surfaces.

In the modification shown in Fig. 1 a plurality of magnetostrictive elements in the form of wires, rods or tubes are arranged parallel to each other without metallic contact with each other. They are spaced from each other by means of two insulating discs 2 provided with suitable holes through which the magnetostrictive elements are

passed. The individual elements 1 can easily be made with exactly the same length so that each has, accordingly, the same tuning as all the others. At the ends of these magnetostrictive elements there are arranged two metallic masses 3 and 4 which are rigidly joined to the elements 1 by soldering, brazing or welding as indicated at 5 and 6. If desired the insulating discs 2 may be omitted and the end masses 3 and 4 may themselves be provided with the proper holes or slits in which the magnetostrictive rods may be inserted so that in this manner all contact between the elements along their longitudinal dimension is avoided.

15 An electromagnetic coil 7 is mounted in a suitable manner around the magnetostrictive elements. When alternating current of the proper frequency corresponding to the frequency of the vibratory structure is passed through the coil 7, 20 the individual magnetostrictive elements and thereby the entire vibratory structure will be set into vibration. A greater effect can be obtained by also providing the coil 7 with a direct current which produces an initial magnetization.

25 By the above construction a vibratory structure is obtained which vibrates as a whole using a definite natural frequency. On the other hand, on account of the rigid connection of the individual magnetostrictive elements with the end 30 masses and by the elimination of insulating material between the individual elements, the losses are reduced to a minimum.

Fig. 2 shows a cross section through the magnetostrictive elements shown in Fig. 1 and demonstrates the manner in which substantially the whole inner surface of the radiating member 4 is provided with magnetostrictive elements. The spacing between the individual elements is made as small as possible consistent with convenient 40 mechanical construction and yet large enough to insure complete electrical and mechanical insulation between the individual elements. By using a multiplicity of magnetostrictive elements covering substantially the whole surface of the radiating mass 4, vibration of the latter as a whole is assured and no bending or diaphragm action takes place. In order to reduce electrical losses in the end masses 3 and 4, these may be slotted or they may be made of a special material of high 50 electrical resistance.

Fig. 3 shows a cross section taken in a similar manner as that of Fig. 2 but of a somewhat different construction. In this case the magnetostrictive elements are in the form of sheet strips 1' which are arranged radially about the longitudinal axis of the vibratory structure. In a manner similar to that shown in Fig. 2 two insulating discs may be provided having radial slits through which the magnetostrictive strips are passed whereby the spacing of the strips from each other is assured. Alternatively the strips may be mounted in radial slots cut in the end masses 3 and 4 to which they are rigidly joined by soldering, brazing or welding or by means of a hardened insulating material or the like. The arrangement of the magnetostrictive elements need not, of course, as in Figs. 2 and 3, be in a circular form, but they may be arranged in any desired configuration to suit the purpose for 70 which the oscillator is to be used.

Fig. 4 shows a sound sender or receiver in which a magnetostrictive vibratory body 8 composed of a multiplicity of magnetostrictive elements is joined to an end mass 9 which is, in turn, fixed to 75 a metal plate 10 of relatively very large mass.

The mass 9 may be fixed to the plate 10 by means of screw threads 35. The other end mass 11 transfers the vibratory energy to and from the surrounding medium, for example, water. A coil 12 surrounds the vibratory elements 8.

5 A cylindrical casing 13 is provided surrounding the whole structure and closed at one end by the plate 10 to which it is secured by means of the screws 36 and made watertight by a gasket 15. The outer surface of the radiating member 11 is 10 covered by a membrane 16 which may be made of thin metal pressed against the member 11 and the casing 13 by means of the clamping ring 17 and the screws 37. It has also been found advantageous to fix the membrane 16 rigidly to the 15 member 11 as by means of soldering, brazing or welding. The coil 12 is connected through conductors 18 to a source of alternating and direct current when the oscillator is used for producing sound waves or with an amplifier when used as 20 a receiver. When alternating current is passed through the coil 12 the end mass 11 is set into energetic vibrations which are transferred to the water as compressional wave energy. On the other hand, if compressional-wave energy strikes 25 the membrane 16 which forms a part of the mass 11, the vibrations are transferred to the magnetostrictive elements 8 and produce an alternating current in the coil 12 which may be amplified and 30 listened to by means of a telephone receiver, or if the frequency is above the audible range, the alternating currents produced in the coil 12 may be made audible by a heterodyne amplifier or other known means.

35 It should be noted that it is important to provide as small a space as possible between the housing 13 and the piston end mass 11 in order to prevent any diaphragm action in the membrane 16 which is used only for the purpose of making the inside of the oscillator watertight. 40 Instead of using the metallic membrane 16 other material may be used, or the membrane may be omitted entirely and the space between the casing 13 and the end mass 11 may be filled with some material such as rubber which is impervious to 45 the water.

50 In the modification shown in Fig. 5 magnetostrictive elements 19 are provided with end masses 20 and 21 designed to vibrate as pistons. The vibratory structure so resulting is supported 55 at a vibratory node by means of a plate 24 of insulating material. If the end members 20 and 21 are of equal mass, the node will be at the center of the elements 19. The plate 24 is secured in a casing formed of two parts 22 and 23 clamped 55 together by means of the bolts 38 made watertight by means of rubber gaskets 31 and 32. The piston radiating members 20 and 21 project through the casing 22 and 23 and have their ends formed in the shape of a truncated cone. The 60 space between the members 20 and 21 and the casing is made watertight by means of the rubber rings 33 and 34. Excitation of the magnetostrictive elements is provided by the coils 25 and 26. These may be connected in series and supplied 65 with alternating and direct current, or one coil may be used for the direct polarization current while the other coil is used for the alternating current.

70 A further feature of the device shown in Fig. 5 is the provision of means for completing the magnetic circuit. This consists of a yoke 27 which completely surrounds the coils 25 and 26. The air gaps 29 and 30 between the yoke and the members 20 and 21 are made as small possible 75

in order to avoid any unnecessary reluctance in the flux path. To reduce losses the yoke 27 is preferably laminated.

Magnetostrictive oscillators constructed according to the principles of the present invention are particularly useful for signaling under water between vessels, particularly submarines, by means of high-frequency compressional waves. These devices are particularly useful in systems 10 for distance measurement according to the echo method. In this instance it is desirable to choose the radiating surface of the oscillator so large that a directional effect is produced in a direction perpendicular to the radiating surface, that 15 is the dimensions of the radiating surface must be large compared to the wave length of the frequency employed. In order to keep the diameter of the radiating surface within reasonable limits it is preferable to choose the natural frequency 20 of the oscillator in the vicinity of or above the audible limit. The excitation of the oscillator may be provided by alternating current produced by a motor-generator or a vacuum-tube oscillator and may be controlled by a key.

25 It has also been found useful to employ an impulse excitation produced by unidirectional current impulses from the discharge of a condenser or by means of the damped vibrations of an oscillatory circuit having a spark gap.

30 Having now described my invention, I claim:

1. Apparatus for producing and receiving high-frequency compressional waves in water comprising a casing having an opening at one end, a mass positioned in said opening and substantially filling the same, means supporting said mass in said position comprising a thin web supporting said mass, means clamping said web at the end of the casing, a great number of magnetostrictive rods substantially covering one surface of said mass, 40 a coil surrounding said rods and means supporting said coil within said casing.

2. Apparatus for producing and receiving high-frequency compressional waves in water comprising a casing having an opening, a mass of substantially rigid material positioned in said opening and filling the same, means freely supporting said mass in said opening to allow motion normal to the surface of the mass, a great number of magnetostrictive rods, means mounting said rods 50 in said mass at the inside of said casing, said rods substantially covering the entire surface of the mass and a coil surrounding said rods for energizing the same.

3. Apparatus for producing and receiving high-frequency compressional waves in water comprising a casing having an opening at one end, a mass substantially filling said opening, means freely supporting said mass for motion transverse to its external surface comprising a thin web 55 supporting said mass and means clamping said web at the end of said casing, a great number of magnetostrictive rods mounted at the end of the mass within the casing and covering substantially the entire surface of said mass, insulating means 60 spacing said rods and securing them in position

with reference to each other, means including in part said casing of magnetic material and said rods and forming a completely closed magnetic circuit through said rods and casing wall and a coil surrounding said rods for energizing the same. 5

4. Apparatus for producing and receiving high frequency compressional waves in water comprising a cylindrical casing, means providing a heavy mass at one end of said casing and closing the same, a plate, a plurality of magnetostriction rods mounted in said plate and positioned normally thereof and substantially covering the whole plate, a mass mounted at the other end of said rods, means attaching said plate to the mass at the end of the casing, the rods running longitudinally thereof and the second mass being positioned in the opening at the end of the casing, means providing a web contacting said second mass and closing the end of the casing and a coil surrounding said rods positioned within the 20 casing for energizing the same.

5. Apparatus for producing and receiving high frequency compressional waves in water comprising a cylindrical casing having an opening at one end, an assembly of parallel magnetostrictive rods 25 closely spaced together but free from each other, a mass positioned at each end of the rods and means mounting the rods in said masses, said rods covering substantially the entire surface of said masses, a coil surrounding said rods and completing the magnetic circuit for the rods about the casing, means for attaching said assembly at one end of the casing and means covering the other end thereof for acoustically transmitting the vibrations to the propagating medium. 30

6. Apparatus for producing and receiving high frequency compressional waves in water comprising a cylindrical casing, an assembly of magnetostrictive rods arranged parallel but close to one another, a mass positioned at each end of the rods in which the rods are mounted, said rods covering substantially the entire surface of said mass, means for fixing the assembly at the back of the casing, a cover fixed to the front end of the casing and contacting said second mass, said rods being arranged parallel to the axis of said casing and a coil positioned within said casing surrounding said rods, said casing and rods completing the magnetic circuit about the coil. 40

7. Apparatus for producing and receiving high frequency compressional waves in water comprising a cylindrical casing having an opening at one end, a mass substantially filling said opening and means providing a thin web for attaching said mass to said casing, a great number of parallel magnetostrictive rods embedded in said mass normal to the external surface thereof, said rods being spaced free from one another but substantially so close together that no more than another rod of the same diameter could be inserted between any two rods, a coil surrounding the whole group of rods and means completing the magnetic circuit for the magnetic field produced by the coil including said rods and the outer casing. 50
